UNITED STATES PATENT OFFICE.

FRANK SANTOMENE, OF NEW YORK, N. Y.

DESIGN FOR A GARMENT-PATTERN.

SPECIFICATION forming part of Design No. 33,213, dated September 18, 1900:

Application filed May 31, 1900. Serial No. 18,672. Term of patent 7 years.

To all whom it may concern:

Be it known that I, FRANK SANTOMENE, a resident of New York, in the borough of Manhattan, county and State of New York, have 5 invented and produced a new and original Design for a Garment-Pattern, of which the following is a clear and exact specification.

The figure of the drawing is a plan view of a garment-pattern, showing my design.

10 The leading feature of my design for a pattern for a garment consists of a body portion the outline of which is as follows: The back edge *a* is curved inward from the bottom upward, then outward, as at *b*, and then inward, as at *c*, to the top *d*, which is curved to the front edge. The front edge is extended down in 15 an inwardly-curved line *e*, then inward, and

terminating at the inner end in the arc of a circle *f*, from which a sleeve-like portion extends outward toward the front and notched 20 at the end, the upper and lower edges of the sleeve-like portion being in curved lines *g* *h*, the lower edge connecting with downwardly-disposed curved lines *i* *j* with a forward curve 25 *k*, from which a line extends to the back.

Having described my design, what I claim is—

The design for a garment-pattern as shown and described.

FRANK SANTOMENE.
